MODULATION

George Lindley Usselman, Port Jefferson, Long Island, N. Y., assignor to Radio Corporation of America, a corporation of Delaware

Original application October 15, 1932, Serial No. 637,923. Divided and this application May 2, 1934, Serial No. 723,425

13 Claims. (Cl. 179—171)

This invention relates to signalling means and in particular to means whereby the characteristics of high frequency oscillations other than amplitude are varied in accordance with signals to be transmitted. This application is a division of my United States application No. 637,923 filed October 15, 1932.

It has been found that ordinary amplitude modulated high frequency oscillations in transmission from the sending station to the receiving station are subject to what is known as fading effects. This is a decided disadvantage since it introduces drop-outs and errors in the signal. Even where diversity receivers are used to receive the amplitude modulated signals the effect of fading is of serious disadvantage.

I have found that if the high frequency oscillations are modulated in phase or in frequency in accordance with the signal to be transmitted they are somewhat less subject to the effect of fading than amplitude modulated waves, assuming like amounts of power are utilized in the transmission. Phase or frequency modulation is advantageous because it allows the transmitter to operate at full output power, whereas in amplitude modulation it is necessary to reduce the power and operate the transmitter at about one fourth of the full transmitter power output. The increased signal strength gained by phase or frequency modulation is a great advantage for reducing fading and for increasing the reliability of the service.

In each of my United States applications, Serial No. 623,558, filed July 20, 1932, Serial No. 616,026, filed June 8, 1932, Patent #2,036,165 dated March 31, 1936, Serial No. 602,487, filed April 1, 1932, Serial No. 607,932, filed April 28, 1932, Patent #2,036,164 dated March 31, 1936, I have shown means for varying at signal frequency the characteristics other than the amplitude of a carrier frequency. In each of these arrangements the carrier frequency is impressed through phase shifting means onto the control grids of a pair of thermionic tubes which have their anodes connected in parallel to a common tank circuit and their internal impedances varied in phase opposition by the signal wave. In each of these arrangements the phase modulator stage comprises two tubes having their input electrodes symmetrically connected and energized as indicated above, and a common tank circuit connected in parallel to the anodes of said pair of tubes.

The present invention relates to an improved modulating means broadly of the type referred to above.

More in detail, this invention relates to an improved modulating means wherein a single phase modulator stage is preceded by an amplitude modulator stage which comprises a pair of tubes having control grids connected in circuits and energized at carrier frequency in phase. In accordance with the present invention each tube is equipped with its own separate tank circuit. Moreover, in the present invention, instead of phase modulating the energy reaching the grids of these two tubes, the phase shifting means is interposed between the separate tank circuits and the control electrode of the single tube in the following stage. Here, as in the prior applications, the internal impedances of the pair of tubes are varied in opposite senses by the modulating frequencies. In the present case this results in amplitude modulation of the carrier. This modulated energy is then fed by way of phase shifting elements to the control grid of the single phase modulator tube.

The novel features of my invention have been pointed out with particularity in the claims appended hereto.

The nature of my invention and the operation thereof will be best understood from the following detailed description thereof and therefrom when read in connection with the drawings, throughout which like reference numerals indicate like parts, and in which:

Figure 1 illustrates a specific embodiment of the invention; while,

Figures 2, 3, 4, and 5 illustrate modifications of the arrangement of Figure 1.

A specific embodiment of my invention is shown in Figure 1. In this figure A is a source of constant frequency oscillations, such as a crystal controlled oscillator or a long line frequency controlled oscillator. The oscillator A is connected in parallel by way of blocking condensers 1 and 3 to the control grids 2 and 4 of tubes G and H respectively of stage C. The tubes G and H are shown as the screen grid type, although three element tubes may be used. In the latter case neutralizing circuits may be necessary. The anode electrodes 6 and 8 of tubes G and H respectively are connected to tank circuits M and N respectively. Tank circuit M includes a variable capacity 10 and an inductance 11. The tank circuit N includes a variable capacity 10' and inductance 11'. The alternating current circuits for tubes G and H are completed by connecting the lower terminals of tank circuits M and N by way of bypassing condensers C₁ to the grounded side of the circuit 12 supplying heating current from the

source K to the cathodes of the tubes. The energizing circuits for anodes 6 and 8 are completed by way of a lead 13 connecting the terminals of inductances 11 and 11' to the source K. Tank 5 circuit M is connected through a blocking condenser O to one end of the phase retarding element L. Tank circuit N is connected through a blocking condenser P to one end of the phase advancing element Q. The other ends of both phase 10 shifting elements are connected together as shown and to the grid S of tube I in stage D.

The alternating current input circuit of tube I is completed by way of radio frequency chocking inductance 14 and by-pass condenser 15 connected between the grid S and cathode 16 of tube I. The cathode 16 is maintained at stable potential by connecting one side thereof to ground G as shown. The desired negative potential may be supplied to the grid S by way of choke coil 20 14 and lead 17 connected with source 18. The alternating current anode cathode circuit of tube I comprises the anode 20, tank circuit R, by-pass condenser 21, and the grounded side of cathode 16. The direct current anode cathode circuit of tube I comprises the anode 20, the inductance 22 of tank circuit R, a portion of the source 18, and the cathode 16. Tank circuit R may be tuned to the desired frequency by a variable capacity 23 connected in parallel with inductance 22. The 25 tube I is of the screen grid type and charging potential is supplied to the screen grid electrode 24 by a lead 25 connected to a point on source 18. Any radio frequency potentials appearing on 24 are shunted around source 18 by a by-pass condenser 26. It will be understood that the screen grid tube I may be replaced by a three-electrode tube provided proper precautions are taken to obtain stable operation thereof. It should be understood that sources K and 18 may be of 30 any desirable type, such as, storage batteries, motor generator sets, or vacuum tube rectifiers.

The tank circuit R of stage D is connected, by way of a line including blocking condenser U, to the stage E. Stage E may consist of limiting 45 devices and either frequency multipliers of amplifiers or both. The last stage is connected by transmission lines V—V to the antenna F.

B represents a source of signal frequency of any nature. The source of modulating potentials, 50 B, is connected with the primary winding 30 of a signal frequency transformer T₁. The secondary winding 31 of this transformer is connected as shown by way of radio frequency inductances 32 and 32' to the control grids 2 and 4 of tubes G and H respectively, as shown. The inductances 55 32 and 32' may be replaced by resistances if desired. In order that radio frequencies appearing in inductances 32 and 32' do not reach the modulation frequency transformer T₁ and source B connected therewith, the lower ends of inductances 32 and 32' are connected by way of bypassing condensers 33 and 33' to the grounded lead of the cathode heating circuit 12. The proper biasing potentials are applied to the control 60 electrodes 2 and 4 by way of the secondary winding 31 and a lead 34 connecting the midpoint thereof to a potentiometer P connected in shunt with a portion of direct current source K. Charging 65 potentials for the screen grid electrodes 36 and 36' of tubes G and H are supplied by way of lead 37 connected to a point on potentiometer resistance P shunted across source K. Alternating current appearing on the grid electrodes 36, 70 36' is shunted around source K by by-pass condensers 38 and 38' connected as shown.

In operation the oscillator A supplies equal amounts of high frequency excitation voltage to each of the control grids 2 and 4 of tubes G and H in stage C. If there is no signal frequency being supplied to the control grids 2 and 4 from B by way of T₁, this high frequency energy will be amplified equally and, if desired, multiplied in frequency in tubes G and H and tank circuits M and N respectively. This follows from the fact that like potentials are applied to the electrodes of these two tubes and also to the fact that tank circuits M and N are made to be of similar characteristics. Furthermore (still assuming no potentials are supplied from B), since in practice the impedances of phase retarding 10 element L and phase advancing element Q are of equal magnitude, the high frequency energy reaching the grid S of tube I in stage D, from tank circuit M and from tank circuit N, will be of equal intensity. The energies will have 15 equal phase angles, that is, one leading and the other lagging, about the average phase position. The resultant phase of the excitation energy supplied to S from M and N will in this case lie 20 midway between the phase angles of the separate 25 energies supplied from M and N. Stage D amplifies, or, if it is desired, may be adjusted to multiply the carrier frequency before it is transmitted to stage E. As I have said before, the carrier energy may be limited and multiplied in 30 frequency or amplified, or both, in stage E. From the last stage, the carrier energy is transmitted through the transmission line V—V to antenna F, where it is radiated into space.

If we now assume that signal frequency is 35 being sent out from source B, the potentials on the grids 2 and 4 of tubes G and H will be varied at signal frequency in phase opposition or, in other words, differentially. Steady negative bias is supplied equally to the control grids 2 and 4 40 of tubes G and H from the battery or source K by way of the midtap of the secondary winding 31 of transformer T₁. The end terminals of this winding carry the bias potential to the control grids 2 and 4. Now take some instant in the 45 signal when the grid 2 of tube G will be swung, say, in a positive direction, while the grid 4 of tube H will be swung an equal amount in a negative direction.

The carrier energy produced in oscillator A 50 is delivered in two equal parts to the grids 2 and 4 of tubes G and H respectively in stage C. One portion is amplified in amplifier G and appears in tank circuit M, while the other portion is amplified in amplifier H and appears in tank 55 circuit N. This amplification is not constant because the amplified energies in the two amplifiers G and H are differentially modulated in amplitude so that the carrier energies delivered by the two amplifiers are of the same phase angle, but of an amplitude which varies at signal frequency and which is proportional to the signal intensity. Due to the action of the modulating transformer T₁ this variation in amplitude is made opposite for each amplifier about an average value. This differential action will increase the power output of tube G and tank circuit M, while the power output of tube H and tank circuit N will be decreased a like amount, or vice versa. The phase deviation or shift caused by 70 L and Q in the two high frequency energies supplied to the grid S of tube I will be equal but the energies will be of unlike sense, and in this case the power supplied from tank circuit M through phase retarding element L will be greater than 75

the power supplied from tank circuit N through phase advancing element Q.

The carrier energy from the tank circuit M connected with amplifier G passes through the phase retarding element L, while the carrier energy delivered by the amplifier H to the tank circuit N passes through the phase advancing element Q. These two differentially modulated carrier energies are impressed on the grid electrode S of tube I at different phase angles because of the action of phase shifting elements L and Q. The impedance of L and Q should be made equal so that they have equal effect on the amplitude of the carrier energies delivered thereby from tank circuits M and N to control grid electrode S. It can be seen that we now have two carrier energies of the same frequency present on the grid S of tube I and that these two carrier energies have a constant phase difference but are of an amplitude which varies differentially about a constant total amplitude or average. In other words, the total energy delivered to the grid S of tube I is constant and the phase angle between the two parts of this energy is also constant. Each of these two parts of the total carrier energy is amplified or multiplied in frequency, or both, in tube I and delivered to the tank circuit R of the stage D. Tank circuit R has only one degree of freedom, that is, the carrier frequency or a desired harmonic of the carrier frequency to which the tank circuit may be tuned so that there can be but one oscillating current in the tank circuit R. Because of the phase difference of the two energies fed into the tank circuit the phase of the oscillating current in the tank circuit will be determined or controlled to a greater extent or made to shift toward that of the carrier energy having the greater amplitude. The amount of the shift will be proportional to the excess energy of one part of the carrier energy over the other part of the carrier energy. The amount of shift in phase of the carrier energy is limited by the value of the reactances of the phase shifting elements L and Q, as has been explained before. This results in carrier energy in the tank circuit R of stage D, which will be of substantially constant amplitude but of varying phase angle. The frequency of the variation of this phase angle is the signal frequency and the degree or amount of phase swing or phase deviation is substantially proportional to the amplitude of the signal. The amount of phase modulation is also controlled by the values of the phase shifting elements L and Q. If the energy in tank circuits M and N are linearly amplitude modulated in phase opposition, the phase of the energy appearing in tank circuit R of stage D will be linearly phase modulated.

The energy delivered from stage D may be utilized in any desired manner. The energy may be amplified or multiplied in frequency and it may be radiated from the antenna F. When the frequency of the phase modulated carrier is multiplied the angle of phase modulation is increased in the same ratio.

In some cases it may be desirable to impress the modulating potentials on the internal impedances of tubes G and H in a different manner than that in which they are impressed on said impedances in Figure 1. For example, it may be desirable to apply the signal oscillations from B by way of the secondary winding of transformer T₁ to the screen grid electrodes 36, 36' of tubes G and H respectively in phase opposition, as shown in Figure 2 of the drawings. When the modulating potentials are applied in phase opposition to the screen

grid electrodes of tubes G and H steady positive charging potential for said electrodes is supplied by way of a lead 37' connected to a point on the resistance of potentiometer P₁ as shown. In this novel modulating scheme the desired negative bias is applied to the control electrodes 2 and 4 of tubes G and H by way of a lead 34' connecting said electrodes to a point on the resistance of potentiometer P. The modulated transmitter of Figure 2 is otherwise the same as the transmitter 10 of Figure 1.

The operation of the arrangement of Figure 2 is similar to the operation of the arrangement of Figure 1. The only difference between the two arrangements is that in Figure 1 the impedances 15 of the tubes G and H are varied in opposition at signal frequency by varying the effective potential on the control grid electrodes, whereas in the arrangement of Figure 2 the impedances of tubes G and H are varied in phase opposition at signal 20 frequency by varying the effective charging potential applied to the screen grid electrodes. In each case the carrier frequency relayed in tubes G and H is differentially modulated in amplitude at signal frequency. 25

In yet other cases it may be desirable to accomplish the amplitude modulation of the carrier in the stage C by means of modulating the anode potentials. When this method of modulating is desired the arrangement of Figure 3 may be used. 30 In Figure 3 the proper negative biasing potentials are supplied to the control grids of tubes G and H by a lead 34' as in Figure 2. Direct current potentials for the screen grid electrodes of tubes G and H are supplied by way of a lead 37, as in 35 Figure 1. In this arrangement, however, the modulating potentials from the source B are supplied by way of transformer T₁ in phase opposition to the anodes 6 and 8 of tubes G and H respectively. In this manner anode modulation in 40 amplitude of the carrier waves passed by tubes G and H is accomplished in the stage C. In other respects the arrangement shown in Figure 3 operates the same as the arrangement of Figure 1. A repetition of the operation of these novel 45 modulating arrangements in connection with Figure 3 is thought unnecessary.

When plate modulation of the amplitude of the carrier in the unit C by a more efficient method is desired, the arrangement of Figure 4 may be used. 50 In this arrangement the tubes G and H are of the three-electrode type. Three-electrode tubes are used in this arrangement because, when the amplitude modulation of the carrier is accomplished by varying the anode potential, the three-electrode tubes give much greater response than that obtainable with the four-electrode tubes of Figure 3. When three-electrode tubes are used the capacity between the anode electrodes and grid electrodes of the tubes G and H may be neutralized by "plate circuit neutralization". This is accomplished by connecting the lower terminal of the tapped plate inductances 11 and 11' to the control electrodes 2 and 4 of the tubes G and H respectively by way of variable neutralizing capacities NC and N'C' respectively. The charging potential for the anode electrodes 6 and 8 is supplied from the lead 13 connected to the midpoint of the secondary winding 31 of transformer T₁ and by leads connecting the ends of the secondary winding 31 of transformer T₁ to the points tapped to the inductances 11 and 11'. The arrangement of Figure 4 is otherwise similar to the arrangement of Figure 3. 55

The phase modulator of Figure 4 operates the 75

same as the phase modulator of Figure 1. The high frequency oscillations from A are impressed cophasally in equal amounts onto the control electrodes of G and H respectively. These oscillations may be amplified or frequency multiplied, or both, in the tubes G and H, and in particular in the output circuits thereof. The high frequency oscillations, whether amplified, frequency multiplied, or both, are differentially modulated 10 in amplitude in stage C in accordance with the signal impressed from source B in phase opposition on the anode electrodes of tubes G and H. The carrier energies from M and N, which are of the same phase but of amplitude which varies at 15 signal frequency, are fed through the phase shifting means L and Q to the control electrode S of tube I. The action of the phase shifted energies from M and N on the control electrode S of tube I results in the production in tank circuit 20 R of energy, the phase of which varies at signal frequency, but the amplitude of which is constant, as has been described in detail hereinbefore in connection with Figure 1. The frequency of the phase modulation of this energy is 25 directly proportional to the signal frequency and the degree of phase shift is proportional to the amplitude of the signal, except as otherwise modified by the phase shifting elements L and Q of stage C. The energy from tank circuit R is fed 30 by way of coupling unit U to the unit E, from which it may be radiated. The unit E may include amplitude limiters or amplitude amplifiers and/or frequency multipliers.

If, for some reason, grid neutralization of the 35 amplitude modulator tubes G and H of stage C is preferable, the circuit arrangement of Figure 5 may be used.

In Figure 5 the source of oscillations A is coupled by way of blocking condensers 1' and 3' to 40 points on the inductance 40 of the grid tank circuit X. This tank circuit X is tuned to the desired frequency by variable capacity 41, and the natural impedance of this tuned circuit X to the oscillations from A is such as to match the low 45 impedance output of A to the high impedance of the input electrodes of tubes G and H. The high frequency oscillations from tank circuit X are applied in phase opposition to the control electrodes 2 and 4 of tubes G and H. The high frequency oscillations repeated or multiplied in tubes 50 G and H are fed to tank circuits M and N, as in the prior arrangement. However, in this arrangement, since the high frequency oscillations 55 are applied in phase opposition to the control electrodes and not cophasally, as in the prior arrangement, reversal of the energy in one of the amplitude modulators G and H must be accomplished in order to properly combine the energies 60 lead through the phase shifting means L and Q to the grid electrode S of tube V. This is accomplished by reversing the coupling of one of the tank circuits M and N with its tube G or H. In Figure 5 the coupling between the tank circuit N 65 and tube H is reversed. In other words, the output circuits of these tubes are, in a manner, connected in push-pull so that the energies therein are alike in phase. The phase shifting circuits L and Q are tapped to points on the inductances 70 11 and 11' such that the energy drawn from the tank circuits M and N is in phase and is fed to the control grid S in phase except for the phase shift accomplished by the phase shifting elements L and Q. In this arrangement the grid to anode 75 capacity of the tubes G and H is neutralized or

compensated by connecting the anode 6 of tube G to the control electrode 4 of tube H and the anode 8 of tube H to the control electrode 2 of tube G by way of neutralizing condensers NC and N'C', as shown. Biasing potential for the control electrodes 2 and 4 of tubes G and H is supplied by way of a lead 34' connecting a point on potentiometer P1 to the midpoint of inductance 40, which has its terminals conductively connected to the control electrodes 2 and 4. The arrangement of Figure 5 is otherwise the same as the arrangement of Figure 4.

It will be noted, however, that in Figures 4 and 5 the inductance 14 of stage D has been replaced by a resistance 14'. It will be understood that 15 either an inductance or a resistance may be used, but it is preferable to use resistance, at this point.

In operation the arrangement of Figure 5 operates substantially the same as the arrangement of Figure 4. However, since there has been a 20 shift in phase of the high frequency oscillations applied to the control electrode 4 with respect to the phase of the high frequency oscillations applied to the same control electrode in Figure 4, there must be a second reversal in phase of the 25 energy accomplished before the energy is applied to the phase shifting elements L and Q and from said elements to the control grid S of modulator tube V. This is accomplished, as indicated above, by reversing the connection between the anode 30 electrode 8 of tube H and the tank circuit N, as shown. This brings amplified and amplitude modulated energies in the tank circuit in phase. The amplified and amplitude modulated and/or frequency multiplied energies in the tank circuits 35 M and N are fed by way of phase shifting elements L and Q to the modulator tube, as in the prior arrangements. This modulation is accomplished in the tube V in the arrangement of Figure 5 and the phase modulated and amplitude 40 modulated energy in the tank circuit R is fed by way of unit E, which may include all of the elements included in the like unit in the prior figures, to the load circuit F.

In the operation of the arrangements shown in 45 Figures 1 to 5 inclusive the tank circuits M and N should be tuned alike, that is, to the same frequency, whether they are tuned to a fundamental or to a harmonic. In some cases it is suggested that a slight amount of mutual inductive coupling between the two circuits M and N be maintained in the proper direction to aid in keeping the two modulator tubes G and H in step. In some cases this should improve the operation 50 of the transmitter. Moreover, it will be understood that the phase shifting elements L and Q may take the form of inductances and capacities, or any combination thereof, or may be replaced by transmission lines of the proper length. These lines may be artificial lines and may include 55 tuning means. All that is necessary is that the desired amount of phase shift is introduced into the amplitude modulator carrier energy reaching the tube V.

Moreover, it will be understood that tubes of 60 any type known may be used to replace the tubes used in the circuits included above, which are intended to be illustrative of the invention and are not intended to limit the invention in any manner except as limited in the claims appended 65 hereto.

When the tubes G and H are used as frequency multipliers as well as amplitude modulators, feed back coupling in these circuits may be resorted to 70 enhance the frequency multiplying effect. This 75

may be accomplished in the arrangements illustrated in Figures 4 and 5 by over-neutralizing the circuits by means of the neutralizing condensers NC and N'C'. That is, the coupling between the 5 input and output circuits of tubes G and H may be increased by these condensers sufficiently to insure the desired amount of regeneration.

Having thus described my invention and the operation thereof, what I claim is:

10 1. Transmitting means comprising, a source of oscillations, a pair of thermionic tubes, means for connecting said source of oscillations in phase to the control electrodes of said tubes, a separate tank circuit connected to the anode of each of said tubes, a source of modulating frequencies, means for impressing the modulating frequencies in phase opposition on the output electrodes of said tubes, a modulator tube, and separate phase shifting means connecting the control electrode of said 15 modulator tube to each tank circuit.

20 2. Means for relaying and phase modulating high frequency energy comprising, a pair of thermionic tubes having their input electrodes energized in phase by a carrier frequency wave, a thermionic modulator tube, phase retarding means for applying energy from the anode of one of said tubes to the control electrode of said modulator tube, phase advancing means for applying energy from the anode of the other of said tubes to the same control electrode of said modulator tube, and means for impressing in phase opposition modulating potentials on the anode electrodes of said pair of tubes.

30 3. Transmitting means comprising, a source of oscillations, a pair of thermionic tubes, a circuit connecting said source of oscillations to the control electrodes of said tubes to apply thereto oscillations of like phase, a separate tank circuit connected to the anode of each of said tubes, there being appreciable coupling between said tank circuits, means for tuning said tank circuits to a frequency which is a harmonic of the frequency of said source, a source of modulating frequencies, means for impressing the modulating frequencies 40 in phase opposition on the anode electrodes of said tubes, a modulator tube, and separate phase shifting means connecting the control electrode of said modulator tube to each tank circuit.

45 4. Signalling means comprising, a pair of thermionic tubes, an input circuit including similar reactances connecting the control electrodes of said tubes together, a separate output circuit connected with the anodes of each of said tubes, symmetrical neutralization circuits connected between the anodes and control electrodes of each of said tubes, means in each of said output circuits for tuning said output circuits to a frequency which is a multiple of the frequency of said input circuit, means for applying high frequency oscillations in 50 phase to the similar reactances in said input circuit, means for varying the impedance of said tubes oppositely at signal frequency, a thermionic phase modulator, and impedances connecting each of said tank circuits to an electrode in said modulator tube.

55 5. Signalling means comprising, a source of constant frequency oscillations, a thermionic modulator tube, a pair of thermionic frequency multipliers and amplifiers having an input circuit and separate anode circuits, a circuit for applying energy of like phase from said source of constant frequency oscillations to the input circuits of said pair of tubes, regenerative coupling between the input circuits and output circuits of said amplifiers and frequency multipliers, means

for applying signal potentials in phase opposition to the anode electrodes of said frequency multipliers and amplifiers, phase shifting means of different character connecting each of said anode circuits to the control electrode of said modulator tube, and a resistance connected between the control electrode and cathode of said modulator tube.

6. In a phase modulation system, a pair of thermionic tubes each having an input electrode energized in phase by a carrier frequency wave, said tubes each having an output circuit, means for tuning said output circuits to a harmonic of the frequency at which the input electrodes are energized, means for producing regeneration in each 15 of said tubes comprising a capacity connecting an output electrode to an input electrode, a circuit for varying the internal impedance of each of said tubes in phase opposition at signal frequency, a utilization circuit, and phase shifting reactances 20 of different character connecting said output circuits to said utilization circuit.

7. Phase modulating means comprising, a pair of thermionic amplifiers and frequency multipliers of the triode type, a common input circuit connected with the input electrodes of said amplifiers and frequency multipliers, means for energizing said input circuit by waves of carrier frequency, an output circuit connected to each amplifier and frequency multiplier, means for tuning the output 30 circuits of each of said amplifiers and frequency multipliers to a harmonic of the energizing frequency, means for insuring controlled regeneration in each of said tubes including a variable capacity connecting a point on the output 35 circuit of each of said tubes to the input electrode of said tube, means for varying the internal impedance of said tubes in phase opposition at signal frequency, a thermionic modulator tube having a resistance connected between its input 40 electrodes, and phase shifting means for connecting said input electrodes to each of said output circuits.

8. Means for relaying and phase modulating carrier frequency energy comprising, a pair of thermionic tubes having their input electrodes energized in phase by a carrier frequency wave, a thermionic modulator tube, a phase advancing reactance for applying energy from the anode of one of said pair of tubes to a control electrode in 45 said modulator, a phase retarding reactance for applying energy from the anode of the other of said pair of tubes to a control electrode in said modulator, and circuits connected with the anode of each of said pair of tubes for impressing modulating potentials on the internal impedances of 50 said tubes.

9. Phase modulating means comprising, a pair of thermionic tubes each having an anode and a control grid, a source of oscillations, circuits 60 for applying oscillations from said source in phase to the control electrodes of said tubes, tank circuits connected with the anodes of each of said tubes, said tank circuits being connected in parallel relation, a modulator tube, a reactance connecting one of said tank circuits to a control electrode in said modulator tube, a second reactance of different character connecting the other of said tank circuits to the control electrode in said modulator tube, and circuits connected with the 65 anode of each tube of said pair of tubes on the one hand and with a source of modulating potential on the other hand.

10. Transmitting means comprising, a source of oscillations, a pair of thermionic tubes, similar 70

- separate reactances connecting said source of oscillations to the control electrodes of said tubes to apply to said control electrodes oscillations of like phase, a separate tank circuit connected to the anode of each of said tubes, means for tuning each of said tank circuits, a source of modulating potentials, circuits connecting said source of modulating potentials in phase opposition to the anode electrodes of said pair of tubes, a modulator tube, separate dissimilar reactances connecting the control electrode of said modulator tube to each tank circuit, and an impedance connected between the control electrode and cathode of said modulator tube.
11. Transmitting means comprising, a source of oscillations, a pair of thermionic tubes, similar reactances connecting said source of oscillations to the control electrodes of said tubes to apply to said control electrodes oscillations of like phase, a separate tank circuit connected to the anode of each of said tubes, means for tuning each of said tank circuits, a source of modulating potentials, circuits connecting said source of modulating potentials in phase opposition to the anodes of said tubes, a modulator tube, separate dissimilar reactances connecting the control electrode of said modulator tube to each tank circuit, a resistance connected between the control electrodes and cathode of said modulator tube and circuits connected with the anodes and control electrodes of each tube of said pair of tubes for neutralizing the effect of the inherent capacity between said electrodes within the tube.
12. In a signalling system, a pair of thermionic tubes each having an anode and a control grid, a common input circuit connected to the control grids of said tubes, a pair of similar reactances in series in said input circuit, neutralizing cir-

cuits connected to the anodes and control grids of said tubes, a separate output circuit connected with the anode of each of said tubes, a circuit connected to a point between said similar reactances for applying carrier waves to be modulated on said input circuit, circuits connected with the anodes of said tubes for varying the impedances of said tubes in phase opposition at signal frequency, a common utilization circuit, and separate phase shifting reactances of different character connecting said output circuits to said common utilization circuit.

13. Modulating means comprising, a pair of thermionic tubes each having an anode, a cathode and a control grid, a source of carrier frequency oscillations, circuits connecting the control grid of each of said tubes to said source of carrier frequency oscillations, a tuned tank circuit connected between the anode and cathode of each of said tubes, neutralizing condensers connected with each of said tubes for neutralizing the inherent capacity between the control grid and anode of each of said tubes, a modulator tube, an inductive reactance connecting one of said tank circuits to the control grid of said modulator tube, a capacitive reactance connecting the other of said tank circuits to the control grid of said modulator tube, an impedance connected between the control grid and cathode of said modulator tube, a utilization circuit connected between the anode and cathode of said modulator tube, a source of modulating potentials, a transformer having its primary winding connected to said source, and circuits connecting the secondary winding of said transformer to the anodes of said pair of tubes.

GEORGE LINDLEY USSELMAN.
